UNITED STATES PATENT OFFICE

2,456,287

WARNING LIGHT FOR VEHICLES

Jeremiah D. Kennelly, Oak Park, Ill.

Application February 1, 1947, Serial No. 725,825

3 Claims. (Cl. 177—329)

1

This invention relates to signal apparatus, and is particularly useful as a signaling or warning device for use on emergency vehicles, trucks, railway cars, etc.

An effective signaling or warning by an emergency vehicle, etc., is becoming increasingly difficult because of the large number of multicolored lights and moving lights encountered in the usual commercial street of a city. At the same time, is extremely important that quick recognition of an emergency vehicle be obtained and the streets promptly cleared so that it can proceed without delay to its destination.

An object of the present invention is to provide a signal device of unique structure which invites immediate attention and which produces prompt recognition of the emergency character of the vehicle. A further object is to provide a mechanism in which there are produced multiple movements of a light-projecting device, the movements being faster in one direction than in another during the operation thereof and producing the impression that the vehicle is moving rapidly in the mind of the observer ahead of the vehicle. Yet another object is to provide a compact unitary device in which multiple movements of a light-projecting device are produced so as to bring about new and effective warning effects. Other specific objects and advantages will appear as the specification proceeds.

The invention is illustrated, in a preferred embodiment, by the accompanying drawing, in which—

Figure 1 is a side view in elevation and a partly vertical sectional view of apparatus embodying my invention; Fig. 2, a transverse sectional detail view, the section being taken as indicated at line 2—2 of Fig. 1; and Fig. 3, a diagrammatic view showing the pattern of movement followed by the light-projecting device.

In the illustration given, 10 designates a casing provided at its front with a lens-supporting ring 11 and carrying a lens 12.

Within the casing 10 is a bracket ring 13 provided with rearwardly-extending lugs 14 and 15. The lugs 14 and 15 are apertured to receive the pivot pins 16 threadedly fixed to the casing 10. With this arrangement, the ring 13 is supported for lateral movement, swinging upon the pivot pins 16.

The ring bracket 13 is provided centrally and on diametrically opposite sides thereof with rearwardly-extending bosses 17 apertured to receive pivot pins 18. The pivot pins 18 are carried by rearwardly-extending ears 19 fixed to a reflector

2

supporting ring 20. Fixed to the ring 20 is the reflector 21 carrying a light bulb socket 22. A light bulb 23 is carried within socket 22 and current is supplied to the bulb 23 through flexible lead connections 24. With the arrangement just described, the reflector 21 swings upon the horizontal pivot pins 18 for vertical movement, while the ring bracket 13 to which the reflector structure is pivoted swings laterally upon the vertical pins 16.

To the rear wall of the casing 10 is secured a casing member 25 and the casing member supports upon it the motor 26. The motor shaft 27 extends downwardly through the casing and is provided at its end with a worm 28. The shaft 27 is also fixed to a worm gear 29. The worm 28 meshes directly with a worm 30 carried by the horizontal shaft 31 and driving at its outer end a disk 32. Eccentrically mounted upon the disk 32 is a drive pin 33 pivotally secured to the drive arm 34. The drive arm 34 is connected by a ball and socket joint 35 to a bracket arm 36 fixed to the lower end of the ring 13. Thus upon rotation of shaft 31, a forward and backward movement of arm 34 is produced and the ring bracket 13 is caused to rotate about pins 16.

The worm gear 29, which is also carried by the motor shaft 27, meshes with the worm 37 on the horizontal shaft 38. The shaft 38 carries a driving disk 39 upon which is eccentrically mounted the pin 40. Drive arm 41 is connected to the pin 42 carried by an angular arm extension 43 of the reflector ring 20. Thus movement of the arm 41 produces a movement of the lever 43 and causes the reflector 21 to tilt forwardly and backwardly.

In the worm and gear structure illustrated, the worm 30 is driven directly by the worm on shaft 27, while the second worm 37 is driven at a much faster speed by means of the greater radius of the worm gear 29. Thus the rotation of the motor shaft 27 produces a slow reciprocation of arm 34 and a rapid reciprocation of arm 34. The result is that the light-projecting means, namely the light bulb or reflector 21, follows the pattern indicated by the lines 44 in Fig. 3. The lines 44 in Fig. 3 indicate that the reflector or light bulb moves upwardly and downwardly seven times while the reflector is being moved laterally a single time. In other words, there are multiple oscillations in the vertical plane during a single oscillation in the lateral plane. It will be understood that the casing 10 may be set in a variety of different positions upon a vehicle so that the oscillations in one direction greatly exceed the

oscillations in another, and such oscillations may be in oblique or angular positions as well as in truly vertical and horizontal planes.

The new effect of the multiple or rapid movements of the light-projecting device in one direction during a slow or single movement of the device in another direction is that there is produced upon the eye of the observer well ahead of the vehicle an immediate impression that the vehicle is approaching rapidly. The rapid vertical swinging of the bulb and reflector, while at the same time being inched laterally in one direction or the other, produces a varying light effect that is sensed by the observer to be the result of great speed. In other words, each vertical swinging of the device, accompanied by a slight lateral movement for a few degrees, combines with the next vertical movement of the device in producing the effect that speed is causing a slight difference in the light beams projected. As a result, the observers in front of the device quickly respond to the warning light, realizing that it is not an ordinary moving light encountered in a city thoroughfare, and give the emergency vehicle right-of-way.

While I have shown a single structure with considerable details for the purpose of illustrating one embodiment of the invention, it will be understood that such details may be varied widely by those skilled in the art without departing from the spirit of my invention.

I claim:

1. In warning light apparatus, a casing open at one end, a lens in the open end of said casing, a light-projecting device within said casing for projecting light beams through said lens, a bracket pivotally mounted in said casing, pivot pins carried by said light-projecting device and supported in said bracket at points extending at right angles to a line connecting the pivots of said bracket, a motor in said casing, connecting arm means driven by said motor for moving said bracket to oscillate the same slowly in a horizontal plane, and a connecting arm driven by said motor and engaging said light-projecting device for oscillat-

ing the same rapidly in an up and down direction whereby a relatively large number of vertical oscillations of said light-projecting device are made during one lateral movement of said bracket.

2. In warning light apparatus, a casing open at one end, a lens in said casing, a light source equipped with a reflector mounted in said casing, a bracket member, pivot pins supporting said reflector in said bracket member for oscillation in a vertical plane, pivot pins supporting said bracket member for oscillation in a horizontal plane, a pair of motor-driven eccentric discs mounted in said casing, and arms connecting said discs to said reflector and said bracket, said discs being rotated at different speeds to produce a number of vertical oscillations of said reflector for a single oscillation of said bracket support.

3. In warning light apparatus, a casing having an opening at one end, a lens in said opening, a motor mounted in said casing and driving a motor shaft, eccentrics driven by said motor shaft, connections between said eccentrics and said shaft for driving one of said eccentrics at a higher speed than the other, a bracket member pivotally mounted in said casing for lateral movement, a light-equipped reflector pivotally mounted in said bracket for vertical movement, a connecting arm between the more rapidly moving eccentric and said reflector, and a connecting arm between the more slowly moving eccentric and said bracket member whereby said light is oscillated in a vertical plane several times while being oscillated a single time in the horizontal plane.
